TIRE

Walter E. Shively and Kenneth R. Lewis, Akron, Ohio,
assignors to The Goodyear Tire & Rubber Company,
Akron, Ohio, a corporation of Ohio

Application June 3, 1957, Serial No. 46,470

Term of patent 14 years

(Cl. D90—20)

Fig. 1 is a partial perspective view of a tire showing our new design; it being understood that the full line portions of the drawing are repeated throughout the circumference of the tire disclosed by means of broken lines;

Fig. 2 is a fragmentary top plan view thereof; and

Fig. 3 is an enlarged cross-sectional view taken on line 3—3 of Fig. 2.

We claim:

The ornamental design for a tire, as shown and described.
